UNITED STATES PATENT OFFICE

158,603

WARM AIR DRIER

Jules Nisenson, New York, N. Y., assignor to Le
John Manufacturing Co. Inc., Huntington,
W. Va., a corporation

Application September 10, 1948, Serial No. 148,538

Term of patent 3½ years

(CL. D86—10)

To all whom it may concern:

Be it known that I, Jules Nisenson, a citizen of the United States of America, residing in the Borough of Manhattan, city of New York, county of New York, and State of New York, have invented a new, original, and ornamental Design for a Warm Air Drier, of which the following is a specification, reference being had to the accompanying drawing, forming part thereof.

Figure 1 is a view in perspective of a warm air drier, showing my new design.

Figure 2 is a rear elevational view of the drier shown in Figure 1.

Figure 3 is a bottom view of the drier shown in Figure 1.

Figure 4 is an enlarged cross-sectional view as seen from the plane 4—4 on Figure 2.

I claim:

The ornamental design for a warm air drier, as shown.

JULES NISENSON.
